ATTORNEY

UNITED STATES PATENT OFFICE

GEORGE W. MILLER, OF SAPULPA, OKLAHOMA

SAND PUMP

Application filed April 2, 1930. Serial No. 441,048.

My invention relates to a combination sand pump and bailer, and more particularly to a device of that character for removing sand or débris accumulated in the bottom of a well during the well drilling operation, the present invention constituting an improvement on the structure disclosed in my co-pending application, Serial No. 301,747, and having for its principal object to provide improved means for connecting the device with a sand line.

In accomplishing this and other objects of the invention, I have provided improved details of structure, the preferred form of which is illustrated in the accompanying drawings, wherein:

Fig. 1 is a vertical section of the lower end of a well hole partially cased, and in which a sand pump and bailer embodying my invention is shown in side elevation.

Fig. 2 is a central vertical section of the upper portion of the device particularly illustrating the pump plunger and its connection with a sand line.

Fig. 3 is a similar view of the lower portion of the device particularly illustrating the trap valve and unloading door.

Fig. 4 is a detail perspective view of the upper portion of the device particularly illustrating attachment of the plunger rod to a sand line, the line cover plate being shown detached from the rod.

Fig. 5 is a detail perspective view of the lower end of the device showing the unloading door open.

Referring in detail to the drawings:

1 designates a well hole partially lined with casing 2, and 3 the combination sand pump and bailer suspended in the well from a sand line 4.

The combination tool includes a tubular body member 5, a bit element having a shank 6 attached to the lower end of the tubular body by a bayonet joint indicated at 7, and a pump barrel 8 connected with the upper end of the body member by a coupling 9, the several parts being presently described in detail.

The bayonet joint connecting the bit element with the tubular body includes a sleeve having a reduced section 10 of a body

member 11 forming a shoulder 12 which seats against the lower end of the tubular body 5, the sleeve being permanently attached to the tubular body member preferably by rivets 13. Slots 14 in the lower end of the body 55 member of the sleeve terminate in lateral sockets or slot portions 15 adapted to interlocking receive lugs 16 formed on the reduced neck 17 at the upper end of the shank portion of the bit element, to form the bayonet joint.

A plate 18 slidable in grooves 19 and 20 in the bit element and body member 11 respectively adjacent one of the slots 15 serves as a latch to hold the bayonet joint in functional position to securely connect the bit element with the tubular body member.

The bit element has an interior channel 21 communicating with the channel of the tubular body and communicating at its lower end with branch outlets 22 and 23 in the bit head over the inclined faces 24 and 25 of said head which converge in the cutting edge 26. A flap valve 27 is mounted on a pivot pin 28 on said head and adapted to seat on a rim 30 75 in the bit channel slightly above the diverging channels, serving to separate said diverging channels from the trap chamber 29 formed as an enlargement of the channel 21 at the bottom of the bit element.

Opening laterally from the trap chamber 29 is a port 31 having a door closure 32 pivoted at its upper end on a pin 33 carried by the body of the bit element and adapted to be held in snugly closed position against the flat face provided about the port opening by a sliding plate 34 movable in the grooves 35 and 36 in the bit head and door element respectively, a pin 34' on the plate being adapted to seat in a notch 35' in the bit head 90 or in a notch 36' in the door member to retain the latch at either limit of its movement.

The door member preferably includes a tongue 32' adapted to seat in a socket 32'' at the bottom of the door frame to stabilize 95 the door in its closed position.

Connected with the upper end of the tubular body 5 by the coupling 9 is a pump barrel 37 provided with ports 38 and having a bail 39 at its upper end including a reduced 100

sleeve 40 fitted within the upper end of the barrel and secured thereto by rivets 42, reduction of the shank to form the sleeve providing a shoulder 41 for seating the shank firmly on the rim of the barrel; the bail arms 43 terminating in a head 44 having a rope channel 45 therethrough and the arms being located diametrically opposite each other, thereby providing an enlarged lateral opening beneath the head through which access may be had to the plunger rod for fastening the sand line to said rod.

46 designates a hollow plunger operable in the pump barrel 8 and having a solid head 47 suspended from a rod 49 having a reduced section 48 on which a valve 50 is mounted for sliding travel between the head 47 and the shoulder 49' at the upper end of the reduced section, the valve 50 being preferably 20 of split construction adapted for assembly about the plunger rod by bolts 51, and having a lower outwardly extending flange forming a cover plate 52 adapted to seat on the head 47 to control ports 53 extending vertically through the head 47 to provide communication between the interior of the plunger and the part of the barrel above the plunger.

The upper end of the plunger rod is provided with a channel 54 registering with the channel 45 of the bail head 44 and enlarged at 55 to form a chamber at the upper end of the rod, a part of the rod being cut away to form a recess 56 through which the chamber 55 is exposed and which is undercut at its upper end to form the retaining lip 57 for a latch plate 59, having a bevelled upper end 60 adapted to seat under the lip 57 and having a recess 61 in its inner face registering 40 with the side of the chamber 55 in the rod body to form an extension of the chamber 55.

An aperture 62 in the lower end of the latch plate registers with a recess 63 in the recessed portion of the plunger rod for receiving a bolt 64 whereby the latch plate is attached to the rod by the bolt and its nut 65.

The purpose of the chamber 55, including the extension 61 in the latch plate, is to accommodate a locking head 58 on the sand line 4 to anchor the plunger rod to the line, the head 58 being preferably formed of a hemp or like cord wound on the end of the line to enlarge the diameter of the line and form 55 a head on the line upon which the rod and its plunger may be suspended. This form of connection of the rod with the line may be effective without the necessity for the usual solder pack, thereby eliminating danger of 60 explosion incident to use of fire for heating the solder in the vicinity of a gas producing well.

When a tool constructed and assembled as described is let into a well, the barrel including the drill bit or other tool elements are

suspended from the sand line by engagement of the upper end of the plunger rod with the bail head 44. As the tool passes downwardly through the well hole, fluid encountered in the well passes up through the branch channels 23 in the bit head, lifting the flap valve 27 and passing out of the barrel through the side openings 38, which are below the plunger when the latter is at the upper limit of its movement, or passing through the 75 plunger, lifting valve 50 and leaving the barrel through the openings between the bail arms.

When the tool reaches the bottom of the well, the fluid in the well may be agitated by the tool to loosen the sand or other fine débris in the well hole so that it may pass into solution in the liquid to enter the barrel for removal. When the agitation has been effected the tool is let down until the barrel is supported on the bottom of the well. Weight of the plunger and its rod then moves the plunger down through the barrel to rest on the shoulder of the bit shank, liquid in the barrel lifting the valve 50 to permit the 90 plunger to descend.

When the plunger has been lowered to its seat at the bottom of the barrel, it is raised by lifting of the sand line. On such upward movement the valve 50 descends and closes 95 the ports 53 so that continued upward movement of the plunger relieves pressure on the flap valve 27, permitting the fluid at the bottom of the well to enter the barrel through the openings 23 and through the valve port. 100 When the plunger reaches the top of the barrel, it contacts the bail arm and the barrel is lifted from the well with its charge of fluid.

At the top of the well the barrel is let down to support on the derrick platform or 105 on the ground, and the outlet door 32 at the bottom of the drill shank opened to empty the barrel of its charge, the ports 38 admitting air to the top of the barrel to facilitate the outflow of fluid.

Should the sand line become worn it may be cut and the lower end removed from the plunger shank through the side of the chamber 55 when the cover plate has been removed and a new section of line run through the 115 channel of the bail head and wound with cord or whatever may be employed to form the anchoring head 58, and replaced in the shank chamber without the necessity for use of fire adjacent the well for heating solder in accordance with common practice.

It is also apparent that by providing the tool with the emptying door 32 removal of any part of the tool to effect the emptying is obviated and that because of the location 125 of the door at the level of the trap valve the entire contents of the barrel may be removed.

Under certain circumstances, for instance in drilling dry holes, the ports 38 may further be employed for introducing liquid to 120

the barrel when the tool is suspended at the top of the well, to seal the plunger and to provide for moistening the formation in the bottom of the well hole.

5 What I claim and desire to secure by Letters Patent is:

1. In a device of the character described including a member having a rope guide at its upper end, a flexible line extended through 10 said guide, and a plunger, a rod connected to the plunger having a channel to receive said line and provided with a side opening for access to said channel, a locking head on the end of the flexible line located in said channel, and removable means for closing said opening.

2. In a device of the character described including a member having a rope guide at its upper end, a flexible line extended through 20 said guide, and a plunger, a rod fixed to the plunger having an axial channel to receive said line enlarged to form a chamber having a side opening adjacent the upper end of said rod, a locking head on the end of the 25 flexible line located in said chamber, and removable means for closing said opening.

3. In a device of the character described including a member having a rope guide at 30 its upper end, a flexible line extended through said guide, and a plunger, a rod connected to the plunger having a channel to receive said line enlarged to form a chamber having a side opening adjacent the upper end of 35 said rod, a retaining lip on the rod, a locking head on the end of the flexible line located in said chamber, a removable cover having one end seated under said lip, and means for securing the opposite end of the cover to said rod.

40 In testimony whereof I affix my signature.
GEORGE W. MILLER.
